H. E. BRYANT

OVERRUNNING PREVENTER FOR WINDING MACHINES

Filed Sept. 16, 1925

Inventor:
Henry H. Bryant,
by weight, Brown, Quincy May,
Attest:

UNITED STATES PATENT OFFICE.

HENRY E. BRYANT, OF PROVIDENCE, RHODE ISLAND, ASSIGNOR TO TUBULAR WOVEN FABRIC COMPANY, OF PAWTUCKET, RHODE ISLAND, A CORPORATION OF RHODE ISLAND.

OVERRUNNING PREVENTER FOR WINDING MACHINES.

Application filed September 16, 1925. Serial No. 56,705.

To all whom it may concern:

Be it known that I, HENRY E. BRYANT, a citizen of the United States, residing at Providence, in the county of Providence and State of Rhode Island, have invented new and useful Improvements in Overrunning Preventers for Winding Machines, of which the following is a specification.

The present invention relates to machines for winding filamentous or strip material by the action of a rotating winding head carrying a supply of such material on an independently rotatable spool or the like. Its object is to prevent continued rotation of the spool after the winding head has been abruptly stopped or quickly retarded. For instance, assuming that the winding head is normally rotated at high speed, and that the machine is equipped with a brake or other stop motion device for quickly arresting the motion of the head when some untoward accident occurs, such as breaking of the stock being wound or its failure to be fed properly to the winding point, then it is desirable to stop the rotation of the stock holding spool or reel also as soon as possible in order to prevent unwinding and snarling of the stock supply, or other danger liable to result from continued free rotation of the supply spool.

I have accomplished this object by providing in connection with the winding head and supply spool, in a machine of the character above indicated, an automatic stop or clutch device which is inoperative so long as the winding head continues to operate in its normal manner, and becomes operative instantly to arrest the spool when the winding head is itself arrested. The embodiment of the invention herein illustrated has been designed for use with a machine for winding strip material into tubular form, and particularly for making flexible metallic conduit or armor for electrical conductors; such a machine being disclosed in my pending application filed February 17, 1925, Serial No. 9,782. The drawings provided with this specification illustrate so much of the said machine as is sufficient for explanation of the principles of the invention and the construction of the specific embodiment

herein referred to. It is to be understood, however, that the invention is not limited to use with that specific machine, but is applicable also to other machines which include a rotating winding head, an independently rotatable spool or equivalent stock holder, and means for stopping the winding head.

In the drawings:

Figure 1 is a side elevation, with a part of the winding head broken away and shown in section, of the machine above referred to having one embodiment of my invention applied thereto;

Fig. 2 is a front elevation of a part of the winding head and a part of the spool with a clutch embodying the present invention in operative association therewith;

Fig. 3 is a sectional elevation taken on line 3—3 of Fig. 2 looking in the direction of the arrows thereof;

Fig. 4 is a perspective view showing a detail of construction of the clutch mechanism in which the present invention is embodied;

Fig. 5 is a cross section on line 5—5 of Fig. 4 illustrating another detail of the mechanism.

Like reference characters designate the same parts wherever they occur in all the figures.

The part of the machine which I have called the "winding head" is that designated by the numeral 21 in the drawings. It is secured on one end of a shaft 22 which rotates in bearings 23 and 24 on a base or frame 25. Such head may be driven by any suitable means, such as a motor 26 mounted on the frame 25 and having a shaft which is coupled with the shaft 22 by a belt or chain 27 and complementary pulleys or sprocket wheels.

The winding head is cylindrical in form, having an end wall 29 and an outer side wall 30. It also has an interior cylindrical bearing surface 31, the said outer wall and bearing being coaxial with the shaft 22. In the annular space between the bearing 31 and the wall 30 is a spool holding the stock 32 and having a hub 33 surrounding and rotatable upon the bearing surface 31, and a flange or base 34 bearing against end wall

29 or against roller bearings mounted in said end wall. The stock as drawn from the spool and carried around a guide roll 35, mounted on the head, and led thence to the 5 winding point. The head is also equipped with stock feeding, forming and laying devices, for a full disclosure of which reference may be had to the aforesaid application; but as such disclosure is not essential to an explanation of the present invention, it is not 10 repeated herein. The requirements of the present disclosure are met by the explanation that the winding head is rotatable and that the stock-holding spool is carried by the 15 head and is independently rotatable relatively thereto about the same axis.

The stock shown illustratively herein is a metallic strip or ribbon wound in the form of a coil and mounted on the spool, surrounding the hub 33 thereof and bearing against the face of flange 34. Such showing, however, is illustrative and typical rather than exclusive. The term "spool" which I have used herein is a generic term intended to 20 include any device similar or equivalent to the so-called spool herein illustrated and adapted to hold a supply of stock in coil form.

When the winding head is rotated to form 30 the stock into the article of manufacture which is the final product of the machine, the spool is rotated also in the same absolute direction, meaning by "absolute direction" the direction with respect to the stationary parts of the machine and other objects, but at a different speed, the speed differential being due to the delivery of stock 35 from the spool to supply the demands of the manufactured article or goods. Thus the 40 spool rotates relatively to the winding head, and the direction of such relative rotation may be the same as, or opposite to, the direction in which the stock is wound to form the coil carried by the spool. The rotation 45 of the head is much more rapid than the relative rotation of the spool, hence when the head is suddenly stopped the spool tends to continue on in the direction of its absolute rotation whether the relative rotation is in the same or the opposite direction. Such continued rotation or overrunning of 50 the spool is liable to have more or less objectionable and serious results, well understood by those acquainted with the art. The 55 object and accomplishment of the invention is to prevent such overrunning.

The direction of rotation of the winding head when winding the stock in the form of a right-hand helix is that indicated by the 60 arrow A in Figure 1 and the arrow B in Figure 2. The coil of strip material is applied to the spool in such a manner that as it is drawn off to satisfy the demands of the manufactured goods for the stock, it 65 causes the relative rotation of the spool to

take place in the direction indicated by the arrow C in Figure 1 and the arrow D in Figure 2. The direction of such relative rotation is opposite to the direction of rotation of the head. Nevertheless the speed 70 of winding is so much greater than the speed of such relative rotation that the absolute rotation of the spool, by which I mean its rotation relatively to the stationary parts of the machine and to other objects, is in 75 the same direction as that of the head. It follows, then, that when the head is suddenly arrested, so that its rate of rotation is greatly reduced, if not instantly stopped, the direction of relative rotation of the spool is reversed, due to the slowing down of the head while the spool continues to rotate with substantially undiminished velocity due to its momentum. I make use of this reversal 80 of relative rotation to effect clutching of the spool and head together when the head is arrested or stopped.

A friction clutch is interposed between the winding head and the spool, said clutch comprising a member 36 adapted to bear on the 90 spool, a holder 37 secured to the winding head and having cam elements 38, and pressure transmitting rollers 39 between the cam elements 38 and the member 36. The member 36 bears on the forward surface of the 95 flange or base portion 34 of the spool, and preferably is provided with a facing of frictional material at the side next to said flange. It forms the primary clutch member adapted to apply to the spool sufficient friction to 100 prevent the latter from moving independently of the head. It is placed in a position where it is overhung by the cam members 38. Said cam members are integral with, or otherwise attached to, the holder 37; and said holder is bolted to the inner side of the outer wall 30 of the winding head. The transmission rolls 39 are confined between lugs 40 on the primary clutch member 36 and are directly under or back of the cam members 38. Said cam members are both inclined in the 110 same direction so as to act in substantially like manner on the rolls.

When the winding head turns in the normal manner and at the normal speed, the surfaces of the cams recede from the rolls 39. The extent of such recession is limited by a stop 41 on the primary clutch arranged to extend across a shoulder on one of the cams 38, so that the clutch member 36 remains in 120 association with the cams while the spool moves past it in the relatively opposite normal direction of rotation. But when the winding head is arrested, with resulting reversal in the direction of relative rotation 125 of the spool and tendency of the spool to run ahead, the cam surfaces bear against the rolls and, through the latter, press the clutch member 36 against the spool. The cams and rolls act in the manner of a roller clutch to 130

obtain a clutching and binding effect on the spool, so as instantly to lock the spool and prevent any overrunning thereof. The entire clutching means thus consists of the primary friction clutch 36 and the roller clutch or clutches comprised by the rolls 39 and cams 38.

The primary clutch member 36 is also preferably applied to exert a constant frictional drag on the spool so as to insure that the spool will be set in rotation when the machine is started up, and will continue in rotation with maintenance of sufficient tension on the stock while the machine continues in operation. Springs 42 are provided for thus constantly pressing the primary clutch member against the spool, such springs reacting against adjustable screws 43 held by lugs 44 projecting from the holder 37, such screws acting through disks 45 which engage with the springs. Each spring and its pressure applying disk are confined in a cup 46 or equivalent guide on the friction member. The disks 45 present a substantially wider area than the ends of the screws, whereby the screws are adapted to move over the disks, with continued pressure application thereon, when such relative motion occurs between the cam holder and the primary clutch as is necessary and sufficient to apply and release pressure through the rolls 39.

It may be understood without special illustration that I may if necessary provide means similar to the stop 41, mounted either on the primary clutch member or on the holder, and positioned to coact with shoulders on the other of said members so as to retain the primary clutch member from displacement radially. Other means to the same end may be provided by the designer within the scope in which I claim protection.

The clutching means herein disclosed is independent of the means for arresting the winding head, and will operate to prevent overrunning of the spool whenever the head is checked, whatever means are applied for the purpose whether automatic or manual. In Figure 1 there is indicated at 48 a device for arresting the head, which device may be the same as that shown for the purpose in my prior application Serial No. 9,782, or a different device, and which typifies generally a means for that purpose. But since the spool clutching means of this invention is independent of the head stopping means, no description of any such stopping means is required for this disclosure.

The device hereinbefore described embodies one form or species of my generic invention in means to prevent overrunning of the supply spool in a winding machine. Other embodiments or species of the invention are disclosed in applications for patent filed

concurrently herewith. The present species is distinguished from the others in that it accomplishes the purpose by the use of a friction clutch; and further in the fact that the same friction clutch also serves as means for normally applying traction to the spool, while the clutch means of the said other species are independent of the traction means with which the machine may be equipped.

Having thus described the principles and one specific embodiment of the invention, although without attempting to describe all possible forms of the invention or all of its modes of use, I declare that what I claim and desire to secure by Letters Patent is:

1. In a winding machine including a rotatable winding head and an independently rotatable spool for the material to be wound, friction means between said head and spool normally resisting relative rotation of the spool, and means for progressively increasing the pressure of said friction means with occurrence and progress of relative movement between the head and spool in one direction.

2. In a winding machine having a rotatable winding head an independently rotatable stock holding spool carried by said head, a traction member connected to the head and bearing frictionally on the spool, and means for increasing the pressure of said traction member in consequence of a reversal in the direction of relative movement between the spool and head.

3. In a winding machine of the character described a rotatable winding head, an independently rotatable and coaxially arranged supply spool, a frictional traction member connected with one of the before named parts and bearing against a complementary surface of the other of said parts, and a secondary pressure applying means constructed to increase the contact pressure between said traction member and the surface with which it is engaged in response to a relative movement between the other of said machine parts and the traction member.

4. A winding machine comprising a rotatable winding head, a coaxially arranged and independently rotatable supply spool, a primary friction clutch member engaged with one of the parts constituting said head and spool so as to partake of the movement thereof, and having frictional sliding engagement with the other of said parts, and means for increasing the friction causing pressure between said clutch member, and the last named part comprising a cam device affixed to the first named part and transmission means between said cam device and the friction clutch.

5. A winding machine comprising a rotatable winding head, an independently rotatable and coaxially arranged supply spool, a friction clutch member engaged with the

head in a manner to cause it to move in unison with the head, but having provision for a limited extent of movement relatively to the head, said friction clutch member being normally in sliding engagement with the surface of the spool, and pressure applying means for increasing the pressure between

the clutch member and the spool when the clutch member is so moved relatively to the head.

10

In testimony whereof I have affixed my signature.

HENRY E. BRYANT.
